UNITED STATES PATENT OFFICE.

EMIL GEORGE HESS AND WILLIAM HESS, OF WEST TORONTO JUNCTION,
CANADA, ASSIGNORS TO ALICE GRACE HESS, OF SAME PLACE.

DESIGN FOR A KNOB OR PULL.

SPECIFICATION forming part of Design No. 21,139, dated October 27, 1891.

Application filed April 23, 1891. Serial No. 390,167. Term of patent 14 years.

To all whom it may concern:

Be it known that we, EMIL GEORGE HESS and WILLIAM HESS, both of the town of West Toronto Junction, in the county of York, in 5 the Province of Ontario, Canada, have invented and produced a new and original Design for Knobs or Pulls, of which the following is a specification.

In the accompanying drawings, Figure 1 is 10 a face view of a knob containing our design, and Fig. 2 is a side view of the same on a slightly-smaller scale.

The leading feature of our design consists 15 of a knob or pull having a series of deep radiating grooves formed in the face of a knob. These grooves form flutings *a*, which are

rounded to the bottom of the groove. The grooves or depressions extend from the apex or center of the knob to the rear part thereof.

Having thus described our invention, what 20 we claim is—

The design for a knob or pull herein shown and described, consisting of a knob the general shape of which is convex or rounded, with a series of grooves or depressions extending from the center of its front face to the rear.

EMIL GEORGE HESS.
WILLIAM HESS.
